CHINESE DECORED BUILDING

Joseph S. Kanter, 1865 NW. 79th St.,
Miami, Fla. 33147

Filed Sept. 9, 1968, Ser. No. 13,441

Term of patent 14 years

Int. Cl. D25—04

U.S. Cl. D13—1

FIG. 3

The side and rear not shown are like the side and front shown.

I claim:

The ornamental design for a Chinese decorated building, substantially as shown and described.
